[57] **CLAIM**

The ornamental design for a loudspeaker, as shown and
described.

DESCRIPTION

FIG. 1 is a top, front and right side perspective view of
a loudspeaker showing my new design;
FIG. 2 is a top, front and right side perspective view
thereof, shown with the grille removed for clarity of
illustration;

FIG. 3 is a front elevational view thereof;
FIG. 4 is a right side elevational view thereof, the left
side being a mirror image;
FIG. 5 is a top plan view thereof;
FIG. 6 is a bottom plan view thereof;
FIG. 7 is a rear elevational view thereof; and
FIG. 8 is a top, front and right side perspective view
thereof. The broken line showing of the stand is for
illustrative purposes only and forms no part of the
claimed design.
